UNITED STATES PATENT OFFICE.

DAVID HAMILTON, OF GREENSBURG, PENNSYLVANIA.

WATER-HEATER.

1,153,781.

Specification of Letters Patent. Patented Sept. 14, 1915.

Application filed November 16, 1914. Serial No. 872,434.

To all whom it may concern:

Be it known that I, DAVID HAMILTON, a citizen of the United States, residing at Greensburg, in the county of Westmoreland and State of Pennsylvania, have invented 5 certain new and useful Improvements in Water-Heaters; and I do declare the following to be a full, clear, and exact description of the invention, such as will enable others skilled in the art to which it appertains to 10 make and use the same.

My invention relates to improvements in water heaters and has for its object to provide an extremely simple device of this character which may be employed for quickly 15 and effectively heating water to be conveyed to a number of radiators or to hot water spigots in a building. In carrying out the above object, I employ the construction hereinafter described and claimed and shown in 20 the drawings wherein:

Figure 1 is a front elevation of a heater constructed in accordance with my invention; Fig. 2 is a central vertical longitudinal section as seen on the line 2—2 of Fig. 25 1; Fig. 3 is a central transverse section taken on the line 3—3 of Fig. 2; and Fig. 4 is a longitudinal section as seen on the plane of the line 4—4 of Fig. 2.

30 In the accompanying drawings forming a part of this application, the numeral 1 designates the lowermost of a plurality of hollow water heating sections, 2 the uppermost of these sections, and 3 the intermediate sections. The section 1 comprises a flat hollow 35 rectangular body 4 and a hollow U-shaped spacing wall 5 which rises from three edges of the body 4 and communicates with the interior of said body as shown in the various

40 figures of the drawings. The two parallel side edges of the body 4 are equipped with the parallel arms 6 of the U-shaped wall, while the connecting portion 7 thereof rises from the rear edge of said body 4, said portion 45 7 being provided with a transversely elongated notch 8 at its upper edge.

By reference more particularly to Fig. 3, it will be seen that a pair of openings 9 having tapered walls are provided in the 50 two arms 6 of the wall 5, said openings receiving the lower ends of barrel-shaped nipples 10 which depend from the bottom of the adjacent intermediate section 3, said bottom also having tapered openings which receive 55 the upper ends of the nipples as shown. The lowermost section 3 as well as the other

intermediate sections, are identical in construction with the section 1, with the exception that they are provided with openings 9 in their bottoms as well as in the upper 60 edges of their U-shaped walls 5. By reference to the various figures, it will be seen that the intermediate sections rest one upon the other with nipples 10 projecting into the openings 9 of adjacent sections, whereby 65 water tight joints are provided.

The uppermost section 2 comprises a hollow rectangular body 4' which is provided with a pair of tapered openings 9' from which two nipples depend into the openings 76 9 of the uppermost intermediate section 3, as shown. With the parts in this position, four upright bolts 20 are passed through ears 20' on the lower section 1 and through similar ears on the upper section 2, said bolts receiving nuts 21 on their upper ends, whereby 75 all of the sections may be held in fixed relation.

Secured to the rear side of the heater thus formed, and having a plurality of slots 25 80 registering with the notches 8 of the various sections, is an upright flue 26 whose upper end is provided with an annular flange 27 for the connection of a suitable draft pipe.

Rising from the uppermost section 2, is a 85 pair of outlet pipes 30 through which heated water is discharged, this water being preferably passed through the radiators and returned to the lowermost section 1 through a return pipe 31 and a second return pipe 31^a, 90 the latter being connected by a T coupling 35 with a water inlet pipe 36 which may lead from any appropriate source of supply, and may, if desired, be provided with a suitable valve (not shown).

95 Spaced laterally from the heater and slightly in advance thereof, is an upright gas supply pipe 40 from which a plurality of horizontal pipes 41 project laterally in front of the various sections of the heater, 100 these pipes 41 being provided with cut-off valves 42 and supporting a plurality of double burners 43 which project into the spaces between the various sections and which are, therefore, partially surrounded by the U-shaped hollow walls above described. For the purpose of effectively lighting the burners 43, a plurality of valved pilot lights 45 are employed, said lights being fed by a pipe 46 which branches from the pipe 40 as 110 shown.

I may here explain that I am aware that

various forms of water heaters have heretofore been placed on the market, but I am not aware that a heater of the class set forth in the claim, has heretofore existed. It will be understood that a device of this character will be extremely efficient since heat radiating in all directions from the burners 43 is utilized, either by contact with the bottom and top walls of the various sections or with the U-shaped walls thereof.

From the foregoing description, taken in connection with the accompanying drawings, it will be seen that a very simple heater has been provided, yet one which will effectively perform the functions for which it is designed.

I claim:

A water heater comprising a flat hollow water heating section, a U-shaped hollow wall 20 formed integrally with said section, rising from the edge thereof, and communicating throughout its length therewith, said wall

having its upper side closed and disposed in a horizontal plane, said closed upper side of the wall being provided with a transverse depression and with an opening communicating with its interior, an additional water heating section resting on said upper edge of the U-shaped hollow wall and having an opening registering with the opening in the upper side thereof, a burner interposed between the two sections and partially surrounded by the hollow wall, an inlet into the first section, and an outlet from the other section, the transverse depression facilitating the discharge of gases from the burner.

In testimony whereof I have hereunto set my hand in presence of two subscribing witnesses.

DAVID HAMILTON.
